UNITED STATES PATENT OFFICE

2,327,000

TRIMMING BOARD

Frank M. Lund, Chicago, Ill., assignor of fifty per cent to Harvey M. Pushker, Chicago, Ill.

Application December 1, 1941, Serial No. 421,125

5 Claims. (Cl. 164—44)

My invention relates to trimming boards, such as those employed for trimming photographs.

The invention has for its object the provision of an improved trimming board having certain desirable features not heretofore employed on this type of equipment.

Trimming boards have been produced for a long period of time wherein a cutting edge was disposed along one side of a generally rectangular member and a cutting knife pivoted near the cutting edge acted to shear sheet material projecting over the cutting edge. Conventionally, this type of trimming board has been provided with cross lines on its upper surface dividing the board into squares, generally one-half inch each way, and, at the top of the board, a scale was provided showing the distance from the cutting edge in either inches or metric figures. This type of trimming board has been identified almost entirely with photographic work and as a consequence has often been referred to as a photographic paper trimmer. Its simplicity and utility have been so well known that its marked disadvantages in many instances have not been given consideration.

As one illustration, it is almost impossible to work in a dark room and expect to get any degree of accuracy, since the paper must be held carefully along the ruled lines in order to square it up for cutting. Even when it is employed outside of a dark room, it is practically impossible to obtain adequate cutting speed because of the time required to true up the paper to the lines ruled on the board. This is particularly true when an attempt is made to use the old trimming board as a semi-production implement, a manner in which it is often used in small photographic establishments. As an example, it may be desired to make enlargement prints of a size not standard, and the most advantageous way of accomplishing this is to cut photographic print paper from larger sheets into sheets of a size desired, and this must be done in a dark room, and the operation may be repeated time after time. The black or brown ruled lines on the old, natural wood colored board, cannot be seen readily in a dark room; if they can be seen faintly, it takes a great deal of time to arrange the paper on the board so that it will cut in the rectangular shape usually desired.

The disadvantages outlined above are illustrative and are suggestive of specific objects of the invention and the functions and advantages secured by my invention, as brought out in the following specification.

In the drawings,

Fig. 1 is a plan view showing a preferred embodiment of a trimming board made in accordance with my invention;

Fig. 2 is an elevational view looking in the direction of the rear of the trimming board;

Fig. 3 is an elevational view looking in the direction of the front of the trimming board;

Fig. 4 is a sectional view taken along the line 4—4 of Fig. 3 looking in the direction of the arrows; and

Fig. 5 is a sectional view taken along the line 5—5 of Fig. 4 looking in the direction of the arrows.

Referring now to the drawings, the trimming board therein illustrated comprises a rectangular base member 10, preferably formed of wood, having strips 11 and 12 preferably running against the grain of the wood to form a firm non-warpable structure, the strips 11 and 12 providing a support for the base member 10. Inset in a recessed portion of one edge of the rectangular base member 10, and preferably partly overlapping the same, is a metal strip 13, secured in place by screws 14, said metal strip having a cutting edge 15 with which the knife or blade 16 is adapted to cooperate to produce a shearing action. A straight edge abutment 17 is secured to another edge of the base member 10 in any suitable manner, as by screws 18, said abutment 17 projecting above the plane upper surface of the base member 10 to form an abutment against which an edge of the paper may lie. The strip 13 carrying the cutting edge 14 and the straight edge abutment 17 are at right angles to each other. The surface face of the base 10 is preferably provided with an ebony finish and is divided into one-half inch squares, dividing lines 19 being provided for such purpose. These dividing lines 19 may, for example, comprise printed or painted lines or, alternatively, they may comprise very narrow grooves cut into the face of the base member 10. In either case, they are preferably white so as to present a color in sharp contrast to that of the surface of the base member 10.

Mounted along the rear of the base member 10 is a guide carrying member or rod 21 which is preferably triangular or hexagonal in cross section. The guide carrying member or rod 21 is secured in any desired manner to the base 10, as, for example, on upstanding posts, and, in the particular embodiment disclosed, it is supported on vertically disposed posts 23 connected to the base member 10 and member 21 by means of the

threaded bolt or stud 22. A guide member 26, formed of a metal strip, is secured at one end to a sliding or slidable member 27, the latter being shaped to provide upstanding ears 28 and 29 having aligned apertures of a cross section corresponding to that of the member 21 for receiving said member 21 and a rearwardly disposed portion or ear 31 threaded to receive a knurled set screw 32. It will be seen, therefore, that the guide member 26 is slidable on the member 21 and may be held in rigid position by engagement with the set screw 32.

The guide member 26 may be clamped and held and maintained flat on the surface of the base member 10 in any suitable manner. In the particular embodiment shown, the end of the guide member 26 which extends over the edge of the base member 10 is provided with an aperture 33 through which a threaded bolt or stud 34 passes, the latter also passing through an aperture 36 of an L shaped member 37 which is attached to the guide member 26 in any suitable way as, for example by means of rivets or pins 38. By tightening the knurled nut 39 on the stud 34 against the washer 41, both the guide member 26 and the lower side of the member 37 are moved toward each other and tightly grip the edge of the base member 10 to hold the guide member 26 against movement and flatly on the surface of said base member 10.

The member 27, when secured by tightening of the set screw 32, is automatically aligned so that the guide member 26 is positioned at exactly right angles to the abutment 17 and parallel to the cutting edge 15. Since the member 27 is self-aligning on the member 21, an operator may make an adjustment of the guide member 26 using only one hand if his other hand is occupied.

The cutting knife 16, which is pivoted to the base member 10, is conventional in character, being provided with the usual handle and cutting blade which latter may be removably secured to the knife shank. These details form no part of my present invention and they are, therefore, not specifically illustrated in the drawings. As shown particularly in Figures 1 and 3 of the drawings, fixed to the cutting knife or blade 16 is a pin or spindle 42 which is mounted for rotatable and slidable movement in a bracket 43 secured to the back of the base member 10 and strip 42 in any desired manner as, for example, by screws 44. A nut 46 is adjustable on a threaded end of the pin 42 to regulate the tension of a spring 47 one end of which is attached to the nut 46 by a screw 48 and the other end of which is attached to the bearing member 49 by a screw 51. A locking nut 52 serves to lock the nut 46 against movement. A relatively small round-headed bolt 53 is secured in a fixed position on a tail piece 54 of the cutting blade. As the drawings show, the portion of the bracket 43 within which the pin 42 is pivoted is rounded but has a slight recess 55.

As described in my prior patent, No. 2,185,985, issued January 2, 1940, the cutting action is as follows: The spring 47 tends to move the pin 42 to the right, when looking at Figure 3, and as the cutting knife is raised to a vertical position, the rounded head of bolt 53 moves to the right with the entire assembly and falls into the recess 55 as a stop so that the cutting blade can be left in an upright position ready for operation. As the blade is brought downwardly, the rounded head of bolt 53 rides out of the recess, throwing the entire blade assembly slightly toward the left, looking at Figure 3, until the blade engages the

straight edge where it is brought still further to the left by this engagement. The tension on the spring 47 is adjusted to control the amount of friction and, therefore, to a certain extent, the cutting action between the blade and cutting edge 15. If it should be desired, considerable tension may be placed on the spring 47 so that, if the cutting blade should be knocked down by accident, its movement will be arrested when it first engages the cutting edge 15 and it will not fall all the way down and possibly cause injury if the fingers or other part of the operator's body should be in the way. It will be noted that the supporting strip 11 projects outwardly from the base member 10 a sufficient distance to act as a stop for the cutting blade.

Instead of employing the particular cutter construction described hereinabove, I may utilize other constructions such as, for example, those described in United States Patents Nos. 1,123,191 and 2,103,217.

The manner of operating or utilizing my trimming board will be apparent in the light of the description which I have given hereinabove. It will be clear that the present construction includes means for truing up, with a minimum of effort, photographic material to be trimmed, and also provides means for preventing accidental dropping of the knife, thereby preventing injury to the operator.

While the form of my invention herein shown and described represents a preferred embodiment, it will be appreciated that various changes in the shape, size and arrangement of parts may be resorted to without departing from the spirit of my invention as set forth in the appended claims.

What I claim as new and desire to protect by Letters Patent of the United States is:

1. A trimming board of the character described comprising a rectangular base member having a metal cutting edge along one side thereof, a cutting knife pivoted to said base member and adapted to cooperate with said metal cutting edge to produce a shearing action, a rod mounted along one side of said base member at right angles to said cutting edge, a guide member slidably but substantially rigidly associated with said rod to maintain the guide member in contact with the base member and arranged for sliding movement in a direction parallel thereto, and means associated with said knife for opposing the downward pivotal movement thereof whereby accidental falling of said knife is avoided.

2. In a trimming board of the character described, a rectangular base member having a metal cutting edge along one side thereof, a cutting knife pivoted to said base member and arranged to cooperate with said metal cutting edge to produce a shearing action, a rod mounted along one side of said base member at right angles to said cutting edge, a guide member having one end slidably associated with said rod and extending at right angles thereto, said guide member being substantially rigidly mounted on said rod to maintain the guide member in contact with the base member but being slidably axially thereof and clamping means at the other end of the guide member means for locking said guide member in position.

3. A trimming board of the character described, comprising a rectangular base member having a metal cutting edge along one side thereof, a cutting knife pivoted to said base member and adapted to cooperate with said metal cutting edge to produce a shearing action, a rod mounted along

one side of said base member at right angles to said cutting edge, a guide member slidably but substantially rigidly associated with said rod to maintain the guide member in contact with the base member and arranged for sliding movement in a direction parallel thereto, said guide member comprising a substantially flat strip attached to a sliding member, said sliding member being shaped to provide a plurality of upstanding ears having alined apertures through which the said rod passes and a rearwardly disposed ear having a threaded aperture, and a set screw threaded therein, said set screw being adapted to lock the sliding member against movement on the rod.

4. A trimming board of the character described, comprising a rectangular base member having a metal cutting edge along one side thereof, a cutting knife pivoted to said base member and adapted to cooperate with said metal cutting edge to produce a shearing action, a rod mounted along one side of said base member at right angles to said cutting edge, a guide member slidably but substantially rigidly associated with said rod to maintain the guide member in contact with the base member and arranged for sliding movement in a direction parallel thereto, said guide member comprising a substantially flat strip attached to a sliding member, said sliding member being shaped to provide a plurality of upstanding ears having alined apertures through which the said

rod passes and a rearwardly disposed ear having a threaded aperture, a set screw threaded therein, said set screw being adapted to lock the sliding member against movement on the rod, and means associated with said knife for opposing the downward pivotal movement thereof whereby accidental falling of said knife is avoided.

5. A trimming board of the character described, comprising a rectangular base member having a metal cutting edge along one side thereof, a cutting knife pivoted to said base member and adapted to cooperate with said metal cutting edge to produce a shearing action, a non-circular rod mounted along one side of said base member at right angles to said cutting edge, a guide member slidably but substantially rigidly associated with said rod to maintain the guide member in contact with the base member and arranged for sliding movement in a direction parallel thereto, said guide member comprising a substantially flat strip attached to a sliding member, said sliding member being shaped to provide two upstanding ears having alined non-circular apertures corresponding in cross-sectional shape to that of the rod and through which the said rod passes and a set screw threaded therein, said set screw being adapted to lock the sliding member against movement on the rod.

FRANK M. LUND.
